UNITED STATES PATENT OFFICE.

GUSTAV FAJEN, OF MILWAUKEE, WISCONSIN.

ROTARY METER.

SPECIFICATION forming part of Letters Patent No. 726,270, dated April 28, 1903.

Application filed July 19, 1902. Serial No. 116,227. (No model.)

To all whom it may concern:

Be it known that I, GUSTAV FAJEN, a citizen of the United States, and a resident of Milwaukee, in the county of Milwaukee and State of Wisconsin, have invented certain new and useful Improvements in Rotary Meters; and I do hereby declare that the following is a full, clear, and exact description thereof.

The improvements consist in certain peculiarities of construction and combination of parts hereinafter particularly set forth with reference to the accompanying drawings and subsequently claimed, the object of the invention being to provide simple, economical, and accurate fluid-meters.

Figure 1 of the drawings represents a plan view of the uncovered lower portion of an improved rotary fluid-meter in accordance with my invention, partly broken and in section; and Figs. 2 and 3, sectional views of said meter respectively indicated by lines 2 2 and 3 3 in the first figure.

Referring by letter to the drawings, A indicates the lower section of a pot-like cylindrical casing, and in practice the upper casing-section (shown by dotted lines in Fig. 2) is held in fluid-tight connection with a continuous outer-rim flange of said lower section, the same as in my Patent No. 661,120, issued November 6, 1900. The lower casing-section aforesaid is provided with an inlet-nozzle *b* and an outlet-nozzle *c*, both of which are made to have connection with pipe through which fluid is conveyed.

Made fast to the bottom of casing-section A by screws *d* or other suitable means are legs *e* of a segmental chamber *B*, that is open at the ends and herein shown arranged eccentric to said casing. The top of the chamber *B* is removable, and a depending hollow branch *f* of said chamber is provided with a seat in which the conical inner end of inlet-nozzle *b* has match fit. A transverse slot in the bottom of the chamber communicates with the depending hollow branch *f*, and back of the slot the opposite chamber-walls are provided with vertical guide-recesses intercepted by a transverse guide-groove in the chamber-bottom. Engaging the guide-recesses and groove

is a sliding gate *C*, that dams the adjacent 50 end of the chamber.

A vertical recess in gate *C* is engaged by a continuous wave-band *D*, set on edge and arranged partly within chamber *B*, the same constituting a loose cam of the variety having 55 equal diameter in every direction measured across its center, whereby it has constant sliding contact with the walls of said chamber.

Inner parallel arms *E F* of chamber *B* serve as bearings for a spindle *G*, constituting part 60 of an ordinary multiplying register mechanism, (not shown,) which in practice is supported outside of casing *A*, generally within a vertical annular flange of the upper casing-section, such a flange being included in the 65 dotted line shown in Fig. 2.

Cam *D* operates as a wiper against a friction-wheel *H*, fast on spindle *G*, this spindle and said wheel therewith being eccentric to said chamber and cam.

Chamber-arm *F* is shown provided with a branch *I*, on which cam *D* is supported.

The contour of cam *D* is such that there is constant pressure thereon when fluid is flowing through chamber *B*, the pressure being 75 on the inner side, outer side, or both, of said cam, according to its constantly-changing position longitudinally of the transverse inlet-slot in the bottom of said chamber, and there is automatic reciprocation of gate *C* incidental to rotary movement of the aforesaid cam. The cam being in rotation, its depressions come into contact with friction-wheel *H* to cause intermittent rotary movement of same and the register-spindle *G*, on which it 80 is made fast. However, other means may be employed for operating the register mechanism coincident with rotation of said cam by fluid-pressure.

Having thus described my invention, what 90 I claim as new, and desire to secure by Letters Patent, is—

1. A rotary meter comprising a casing having a fluid-outlet, a segmental chamber in the casing open at the ends and in communication 95 with a fluid-inlet, a sliding gate damming the chamber back of said inlet, a continuous wave-band constituting a cam on edge partly within

the aforesaid chamber in engagement with the gate to have constant sliding contact with opposing chamber-walls, and means coöperative with the cam to impart motion to register mechanism.

5. 2. A rotary meter comprising a casing having a fluid-outlet, a segmental chamber in the casing open at the ends and in communication with a fluid-inlet, a sliding gate damming the chamber back of said inlet, a continuous wave-band constituting a cam on edge partly within the aforesaid chamber in engagement with the gate to have constant

sliding contact with opposing chamber-walls, a loose register-mechanism spindle, and a 15 friction-wheel fast on the spindle in position to be actuated at intervals by the cam.

In testimony that I claim the foregoing I have hereunto set my hand, at Milwaukee, in the county of Milwaukee and State of Wisconsin, in the presence of two witnesses.

GUSTAV FAJEN.
